[57] CLAIM

The ornamental design for a telephone, as shown and described.

DESCRIPTION

FIG. 1 is a front, top and right side perspective view of a telephone showing our new design;

FIG. 2 is a front elevational view thereof;

FIG. 3 is a top plan view thereof;

FIG. 4 is a rear elevational view thereof;

FIG. 5 is a bottom plan view thereof;

FIG. 6 is a left side elevational view thereof;

FIG. 7 is a right side elevational view thereof; and

FIG. 8 is a front, top and right side perspective view thereof with a stand pivoted to the bottom of the telephone base rotated into projected position for supporting the base in an upwardly and rearwardly oblique position.
